UNITED STATES PATENT OFFICE

172,582

CLOCK

Paul G. Darrot, Southbury, Conn., assignor to
General Time Corporation, New York, N. Y.,
a corporation of Delaware

Application August 6, 1953, Serial No. 26,332

Term of patent 14 years

(Cl. D42—7)

To all whom it may concern:

Be it known that I, Paul G. Darrot, a citizen of the United States, residing at Southbury, in the county of New Haven and State of Connecticut, have invented a new, original, and ornamental Design for a Clock, of which the following is a specification, reference being had to the accompanying drawing, forming a part thereof.

Figure 1 of the drawing is a front elevational view of a clock embodying my new design.

Figure 2 is a top perspective view thereof.

I claim:

The ornamental design for a clock, substantially as shown and described.
